(57) **CLAIM**

The ornamental design for a combined eye mist applicator and reservoir, as shown and described.

DESCRIPTION

FIG. 1 is a right side elevational view of a combined eye mist applicator and reservoir with the applicator positioned over the reservoir showing my new design;

FIG. 2 is a left side elevational view thereof with the applicator detached from the reservoir;

FIG. 3 is a rear elevational view of FIG. 1;

FIG. 4 is a front elevational view of FIG. 1;

FIG. 5 is a top plan view of FIG. 1; and,

FIG. 6 is a bottom plan view of FIG. 1.
